UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

CAR TRUCK.

Application filed April 25, 1921. Serial No. 464,243.

To all whom it may concern:

Be it known that I, DONALD S. BARROWS, a citizen of the United States, residing at Rochester, in the county of Monroe and 5 State of New York, have invented certain new and useful Improvements in Car Trucks; and I do hereby declare the following to be a full, clear, and exact description of the invention, such as will enable others 10 skilled in the art to which it appertains to make and use the same.

My invention relates to railway car trucks, and has for its object to produce a strong, durable and efficient structure which well 15 lends itself to the employment of the most reliable materials for resisting the strains to which the parts are subjected in service, and which is economical in respect to maintenance cost not only because the structure is 20 capable of withstanding great strains without injury, but also by reason of the facility with which repairs may be made. In car trucks employing cast steel side frames an injury to the frame generally renders it entirely worthless, whereas in a truck constructed in accordance with my invention injuries to parts of the side frames only necessitate replacing the damaged parts with new 25 ones.

30 One of the principal features of the invention consists in forming the side frames of a truck as trusses involving a compression member, a strut, and a tension member which is looped over the ends of the compression member and between which and 35 said compression member the strut is interposed.

A further feature of the invention consists in constructing the truck with trussed 40 side frames each of which involves a compression member, a tension member, and a strut interposed between said members, the tension member being provided with looped ends girdling the respective ends of the compression member and non-rigidly engaging 45 the strut so as to permit the equalization of strains in the tension member.

A still further feature of the invention 50 consists in constructing the truck with trussed side frames each involving a tension member, a compression member, and a strut interposed between said members, the ends 55 of the said compression member being girdled by the tension member in a manner per-

mitting the compression member to adjust 55 itself with respect to the tension member so as to relieve the latter of lateral bending strains.

Another feature of the invention resides 60 in providing the compression members of the truck side frames with curved seats or bearings for the tension member, the said seats being so disposed that their axes of curvature are in the planes of the respective 65 side frames.

A further feature of the invention consists 70 in providing the trussed side frames of a truck with a continuous tension element having spaced portions which are maintained in spaced relation by a portion of the neighboring strut member of the truss.

Another feature of the invention consists 75 in providing a trussed side frame with a tension element having spaced portions and in employing journal box tie members which are connected to the neighboring strut member of the structure in vertical alinement with the spaces between the adjacent spaced portions of the tension element.

Another feature of the invention consists 80 in employing a compression member which is of greater depth and less width adjacent its ends than at its center.

Another feature of the invention consists 85 in employing in trussed side frames compression members whose cross sectional form at some points is different from that at others, the peripheral length of the several cross sections nevertheless being equal.

Another feature of the invention consists 90 in constructing a trussed side frame with a tension member which is looped over the ends of the compression member and which is of twisted form at a point between said compression member and the strut member 95 of the truss.

A still further feature of the invention consists in constructing a side frame truss with a compression member, a strut and a tension member looped around the compression member and having spaced portions 100 operatively connected to the strut, and in combining therewith a journal box tie member of twisted form which extends between the said spaced portions of the tension member.

Another feature of the invention resides 105 in forming a side frame with a compression

member, a strut and a tension member combined in trussed relation, the said tension member being fashioned as a band of uniform cross section looped around opposite ends of the compression member and having portions of twisted form extending between the compression member and the strut.

There are other features of the invention residing in details of elements and in particular combinations of parts, all as will hereinafter appear.

In the drawings chosen for the purpose of illustrating the invention, the scope whereof is pointed out in the claims,—

15 Figure 1 is a view, partly in side elevation and partly in vertical section, of a car truck embodying the invention, the truck wheels being indicated in dot and dash lines, a portion of the bolster being broken away and certain of the bolster springs being omitted.

20 Figure 2 is a plan view of the truck side frame illustrated in Fig. 1, the journal boxes being omitted.

25 Figure 3 is a detail sectional view on the line 3—3, Fig. 1.

Figure 4 is a detail sectional view on the line 4—4, Fig. 2, a portion of the neighboring journal box being also shown.

30 Figure 5 is a detail inverted plan view of the lower end of the center casting or strut member of the trussed side frame illustrated in Figs. 1 and 2.

Figure 6 is a detail sectional view on the line 6—6, Fig. 1.

35 Figure 7 is a detail sectional view on the line 7—7, Fig. 1.

Figure 8 is a view corresponding to Fig. 4, but illustrating a modified form of construction.

40 Figure 9 is a view, partly in side elevation and partly in vertical section, of a modified form of car truck embodying my invention, the truck wheels being indicated by dot and dash lines, a portion of the bolster being broken away and certain of the bolster springs being omitted.

Figure 10 is a view, partly in plan and partly in horizontal section, of the truck side frame illustrated in Fig. 9.

50 Figure 11 is a detail sectional view on the line 11—11, Fig. 9.

Figure 12 is a detail sectional view on the line 12—12, Fig. 9.

55 Figure 13 is a detail view in inverted plan of the lower central portion of the side frame shown in Fig. 9.

Figure 14 is a detail sectional view on the line 14—14, Fig. 9.

60 Figure 15 is a view, partly in side elevation and partly in vertical section, of a modified form of car truck embodying the invention, the truck wheels being indicated by dot and dash lines, a portion of the bolster being broken away and some of the bolster springs being omitted.

Figure 16 is a view, partly in plan and partly in horizontal section, of the truck side frame illustrated in Fig. 15, the bolster and bolster springs being omitted and a portion of the spring plank of the truck being 70 broken away.

Figure 17 is a sectional view on the line 17—17, Fig. 16.

In the drawings,—

1 indicates the wheels of a car truck. The 75 journal ends of the axles (not shown) upon which the truck wheels are mounted co-operate with journal boxes 2 which may be of any usual or desired form, but which, as shown, are preferably connected to the adjacent side frame truss by journal box bolts 3 in a well known manner.

Each of the side frames, which are or 80 may be of identical construction, involves a plurality of elements combined in trussed 85 relation, said elements preferably consisting of a unitary compression member 4, an integral center casting 5 which functions as a strut, and a continuous tension member 6

which girdles the ends of the compression 90 member and passes beneath the lower part of the center casting or strut 5. The strut casting 5 is preferably made of U-form, providing truck columns 7 which are integrally 95 united at their lower ends by a bolster spring seat 8 upon which the truck spring plank 9 rests and to which it is secured. The bolster 10 is guided for vertical movements

between the columns 7 of the center casting and is yieldingly supported by bolster 100 springs 11 which are seated upon the spring plank in the usual manner. If desired the columns 7 of the center casting or strut may be protected from wear by means of

chafing plates 12 which are interposed between the sides of the bolster 10 and the 105 respectively adjacent columns 7. When such chafing plates are employed they are preferably constructed of channel form (see Fig. 7) and may be attached to the respective 110 columns by means of countersunk rivets 13.

To relieve these rivets of shearing strains due to vertical movements of the bolster while in contact with either of the chafing 115 plates 12, the columns 7 of the strut member 5 are preferably provided on their opposed inner faces with spaced ribs or lugs 14 which by engaging the opposite ends of the corresponding chafing plates prevent vertical movement of the latter.

The upper end of the strut member 5 is 120 suitably secured to the compression member 4, as for example, by means of rivets 15, while the lower end of the strut member is provided adjacent its opposite outer faces 125 with curved seats 16 against which correspondingly spaced portions of the tension member 6 bear when the parts are in assembled relation. As shown in Figs. 3 and 6, the lower end of said strut extends be- 130

- tween the spaced portions of the tension member 6 so as to prevent the latter from moving toward each other, while outward separation of the spaced tension member 5 bars is preferably restrained by means of a yoke or clamp member 17 having upwardly extending arms or lugs 18 between which and the neighboring vertical faces of the strut the spaced portions of the tension member 6 pass. The yoke 17 may be conveniently secured to the center casting or strut 5 by means of rivets 19. Such a form of construction provides means for operatively combining the tension member and strut in a manner permitting the tension member to adjust itself with relation to the strut when the truck is in service so as to permit an equalization of the strains in the tension member.
- 20 The center casting 5 is preferably provided adjacent the lower ends of the columns 7 with webs or flanges 20 to which journal box tie members 21 may be rigidly secured by means of rivets 22. The flanges 20 are spaced between the curved seats 16 of the strut so that they project between neighboring spaced portions of the tension member 6, thus allowing the journal box tie members 21 to be disposed in vertical alignment with the spaces between neighboring portions of the tension element of the truss. Each of the columns 7 of the strut 5 may be provided adjacent its upper end with a suitable brake hanger bracket 23 to which brake hangers 24 are respectively connected by means of suitable pivot pins 25. Instead of casting the brake hanger brackets 23 integral with the strut casting, they may, as shown, be formed as separate castings rigidly connected to the strut member by means of rivets.
- The top arch bar or compression element 4 of the truss may advantageously be of pressed steel and formed from a blank or sheet having parallel sides, such a form of blank being desirable from the standpoint of economical manufacture. The compression member is preferably of less depth and greater width adjacent the strut 5 than at points over the journal boxes adjacent the tension member 6, the cross sectional form of said compression member being preferably gradually varied towards its ends from the strut member. By this means the metal is efficiently disposed to resist the strains to which the structure is subjected in service. At its opposite ends the compression member 4 is curved transversely to provide seats 26 against which the looped ends of the tension member 6 bear. The axes of curvature of these seats are in the plane of the side frame of the truck and pass through the loop of the tension member element. As the tension element 6 girdles the ends of the compression member 4 without being rigidly connected thereto, the curved bearing faces 26 permit the compression member to adjust itself with respect to the tension member so as to relieve the latter from any substantial lateral bending strains.
- Suitable fillers or reinforcing castings 27 are interposed between the ends of the channel compression member 4 and the respectively adjacent journal boxes 3. The castings 27, which are suitably apertured to receive the journal box bolts 3, may be secured to the compression member by means of rivets 28 and 29 which, in order to minimize the strain thereon, may be advantageously located as shown. The rivets 29 preferably have their heads flattened on one side so as to engage the tension member 6 and ensure its retention in proper relation to the curved seats 26 of the compression member.
- In order to permit the withdrawal of the journal box bolts 3 at the inner sides of the journal boxes, the compression member is provided adjacent its opposite ends with openings 30 of a size sufficient to permit the passage of the said bolts.
- The tension element 6 of each side frame passes beneath the center casting or strut member 5 and girdles the opposite ends of the compression member 4. It is preferably formed as an integral endless loop or hoop affording spaced parallel portions or tension members which operatively connect each end of the compression member 4 with the center casting or strut, the continuous character of the tension member and its loop form enabling it to be operatively combined with the strut and with the compression member of the truss without the intervention of rivets, bolts or other similar connecting means.
- The truck illustrated in Figs. 1 to 7, inclusive, may be assembled in the following manner: After the center casting or strut 5 and the compression member 4 have been riveted together, and after the reinforcing castings 27 have been attached to the compression member by means of the rivets 28, the looped tension member 6 may be dropped down over the compression member, its spaced portions being spread apart so as to permit it to clear the spring seat 8 at the lower end of the center casting. The spaced portions of the tension member 6 are then forced toward each other so as to bring them into assembled bearing relation with the correspondingly curved seats 16 upon opposite sides of the strut 5. The slack necessary to enable the tension member 6 to be brought into assembled relation to the strut may be obtained either by bending the outer ends of the compression member 4 downward or by heating the tension member until its spaced side portions can be slid into position beneath the shelves 16 of the center casting, or a combination of these two modes of assembly may be adopted. After the two sides 105 110 115 120 125 130

of the tension member 6 have been brought into proper engagement with the seats or shelves 16 the yoke or clamp member 18 is put in place and riveted to the lower end of 5 the strut 5. The brake hanger brackets 23 and the journal box tie bars 21 may thereafter be riveted in place and the journal boxes 3 secured in position by means of the bolts 3 which pass through the respective tie 10 members 21 and the reinforcing castings 27.

The reinforcing casting 31 illustrated in Fig. 8 performs all the functions of the reinforcing castings 27 heretofore described and in addition serves to maintain the tension member 6 in assembled relation with the compression member 4 of the side frame. To this end the reinforcing member 31 is provided with a lug 32 which overlaps the upper edge of the tension member 6 where 20 it passes around the compression member. In respect to the maintenance of the tension member in proper relation to the compression member of the truss, the lug 32 performs the same function as the rivet 29 of 25 the construction illustrated in Figs. 1 to 7, inclusive. With the exception that the aperture 30 in the compression member 4 is sufficiently enlarged to receive the lug 32, the compression member of the structure shown 30 in Fig. 8 is preferably of the form heretofore described.

In the form of my invention illustrated in Figs. 9, 10, 11, 12, 13 and 14, the truck wheels 1, journal boxes 2, journal box bolts 35 3, compression member 4, spring plank 9, bolster 10, bolster springs 11, bolster chafing plates 12, and reinforcing castings 27 are, as shown, of the same or substantially the same construction as the corresponding 40 parts embodied in the structure already described. The center casting or strut 33 in this modified form of my invention, is also generally similar to the strut member 5, but its lower end is slightly modified to provide curved bearing faces 34 of a width 45 equal to the greatest transverse dimension of those portions of the tension member 35 which pass beneath the strut. At the outer edges of the respective seats 34 the center casting or strut 33 is provided with flanges 36 which by engaging the neighboring vertical faces of the spaced portions of the tension member 35 prevent separation of the latter. As more particularly shown in Fig. 50 14, a portion 37 of the lower end of the strut 33 projects downwardly between the spaced segments of the tension member 35 so as to prevent them from moving toward each other. The center casting 33 is provided adjacent the lower end of its bolster columns with oppositely disposed vertical flanges 38 which project between the adjacent spaced portions of the tension member 60 of the trussed structure. The webs or 65 flanges 38 permit the vertical portions 39 of

twisted journal box tie members 40 to be readily secured at their inner ends to the strut 33 by means of rivets 41.

The tension member 35, which passes under the strut 33 and is looped or girdled 70 around the opposite ends of the compression member 4, is provided with spaced portions which are of twisted form at points intermediate of said compression member and said strut. This construction enables the 75 tension member to have an extended bearing both upon the compression member 4 and upon the center casting 33, thereby counteracting any tendency of the tension member to twist or rock upon the other 80 members of the truss with which it is combined. This form of construction is also advantageous in that while allowing the depth of the truss to be relatively great it increases 85 the clearance of the truck side frames above the track rails, thereby allowing the truck wheels to be turned down to smaller diameters without the necessity of so soon inserting liners over the journal boxes in order to maintain the required rail clearance. 90

Except as hereinafter described the modified form of construction illustrated in Figs. 15, 16 and 17 is or may be the same or substantially the same as that shown in Figs. 95 1 to 7, inclusive, and accordingly corresponding parts have been indicated by like reference numerals. In this form of my invention the strut elements of the side frame trusses are each composed of a plurality 100 of members 42, 42 and 43 instead of being formed as a single casting, while the tension member 44, instead of being fashioned as an integrally united endless loop, has the ends of the bar from which it is formed overlapped and rigidly riveted to the spring 105 seat member 43 of the strut by means of rivets 45. The upper edges of the spaced portions of the tension member 44, which girdles the compression member 4, bear against suitable seats 46 on the under surface of the member 43 of the strut, and said member 43 is provided with a downwardly projecting portion 47 which extends between the spaced portions of the tension member 110 so as to prevent them from moving 115 toward each other. The overlapped ends of the tension member are prevented from moving outwardly away from the bottom of the strut by means of the rivets 45, while the portion of the tension member 44 which 120 is on the opposite side of the strut may be restrained from outward movement by means of a lug 48 with which the member 43 may be conveniently provided. The members 42 of the strut, which form the truck 125 columns, are preferably secured to the spring seat member 43 of the strut by the rivets 49 by which the inner end of the journal box tie members 21 are secured to the strut. 130

I claim:—

1. A truck side frame comprising a plurality of elements combined in trussed relation, said elements involving a compression member, a strut, and an integral tension member formed as a loop.
2. A truck side frame comprising a compression member, a tension member, and a strut interposed between said members, said tension member being formed as an endless bar constituting a loop.
3. A truck side frame comprising a plurality of elements combined in trussed relation, said elements involving a compression member, a strut, and a tension member of loop form.
4. A truck side frame comprising a compression member, a strut, and tension resisting means operatively combined with said compression member and strut in trussed relation, the ends of said tension resisting means being formed as loops passing around said compression member.
5. A truck side frame comprising a compression member, a strut, and tension resisting means combined with said compression member and strut in trussed relation, said tension resisting means being provided at its opposite ends with loops through which the respectively adjacent ends of said compression member project in the direction of length of said member.
6. A truck side frame comprising a plurality of elements combined in trussed relation, said elements involving a compression member, a strut, and a tension member, said tension member being provided with a loop whereby it is adapted to be operatively connected to said compression member, and said loop being formed with spaced portions each of which is operatively connected to said strut independently of the other.
7. A truck side frame comprising a plurality of elements combined in trussed relation, said elements involving a compression member, a strut, and a tension member having spaced portions extending from said strut to said compression member and between which said compression member extends, said spaced portions being connected by a portion of said tension member extending over said compression member.
8. A truck side frame comprising a plurality of elements combined in trussed relation, said elements involving a compression member, a strut, and a tension member operatively connecting said compression member and said strut, said tension member being looped over said compression member.
9. A truck side frame involving a compression member, a tension member, and a strut interposed between said members, said tension member being non-rigidly connected to said strut so as to permit equalization of strains in said tension member and being

provided with looped ends girdling the respective ends of said compression member.

10. A truck side frame involving a compression member, a tension member, and a strut interposed between said members, the ends of said compression member being girdled by said tension member, and said compression member and said tension member being non-rigidly connected so as to permit said compression member to adjust itself with respect to said tension member and thereby relieve said tension member of lateral bending strains.

11. A truck side frame involving a flanged compression member, a tension member, and a strut seated between the flanges of the said compression member and interposed between said member and the tension member, said compression member and said tension member being connected with capability of relative movement permitting said compression member to adjust itself with respect to said tension member and thereby relieve said tension member of lateral bending strains.

12. A truck side frame involving a compression member, a tension member, and a strut interposed between said members, said tension member being non-rigidly connected to said strut, and said compression member and said tension member being connected with capability of relative movement permitting said compression member to adjust itself with respect to said tension member and thereby relieve said tension member of lateral bending strain.

13. A truck side frame involving a compression member, a tension member, and an interposed strut, said compression member having curved seats for said tension member, the axes of curvature of said seats being in the plane of the side frame.

14. A truck side frame involving a compression member, a tension member, and a strut combined with said members in trussed relation, said compression member being formed with a curved seat for said tension member, the axis of curvature of said seat being in the plane of the side frame.

15. A truck side frame involving a compression element, a tension element, and an interposed strut, portions of said compression element being curved transversely of said frame to form seats for said tension element.

16. A truck side frame involving a compression element, a tension element, and an interposed strut, said compression element having curved seats for said tension element, the axes of curvature of said seats being at an angle to each other.

17. A truck side frame involving a compression member, a tension member, and a strut interposed between said members, said tension member having spaced portions, and

90

100

105

110

115

120

125

130

18. A truck side frame involving a compression element, a tension element having spaced portions, a strut operatively interposed between said elements and constituting means for maintaining said spaced portions of said tension element in spaced relation, and means for preventing separation 10 of said spaced portions of said tension element adjacent said strut.
19. A truck side frame involving a compression element, a tension element having spaced portions, a strut operatively interposed between said elements, and journal box tie members connected to said strut in vertical alinement with the space between said spaced portions of the tension element.
20. A truck side frame involving a compression element, a tension element having spaced portions, a strut operatively interposed between said elements, and journal box tie members extending between said spaced portions and connected to opposite 25 sides of said strut.
21. A truck side frame involving a compression element, a strut, and tension means vertically overlapping a portion of said strut, said tension means having spaced portions 30 extending along the lower end of said strut adjacent the opposite outer faces of the latter.
22. A truck side frame involving a compression element, a tension element having spaced portions, a strut operatively interposed between said elements, and means carried by said strut for preventing outward lateral displacement of said spaced portions with respect to said strut.
23. A truck side frame involving a compression member, a separate tension member, and a strut combined in trussed relation, said compression member being of greater depth and less width adjacent its ends than 45 at its center.
24. A truck side frame involving a compression member, a separate tension member, and a strut interposed between said members, said compression member being of less depth and greater width adjacent said strut than at points adjacent said tension member.
25. A truck side frame involving a pressed steel compression member, a strut, and a separate tension member, said compression member being of greater depth and less width adjacent its ends than at the center and being formed from a blank having parallel sides.
26. A truck side frame comprising an independent tension member, a flanged compression member the flanges thereof being downwardly extended, and a strut combined with said members in trussed relation, said 60 strut fitting within the flanges of the com-
- pression member, said compression member being of greater depth adjacent its ends than at its center.
27. A truck side frame comprising a tension member, a compression member, and a strut combined with said members in trussed relation, the cross-sectional form of said compression member at some points being different from that at others, and the peripheral length of said cross-sections being equal.
28. A truck side frame comprising a compression member, a strut, and a tension member combined in trussed relation, said tension member being looped over the ends of said compression member and portions of said tension member between said compression member and said strut being of twisted form.
29. A truck side frame comprising a compression member, a strut, a tension member, and a journal box tie member, said tension member being looped around said compression member and having spaced portions operatively connected to said strut, and said tie member being of twisted form and extending between said spaced portions of said tension member.
30. A truck side frame comprising a compression member, a strut, a tension member, and a journal box tie member, said tension member being looped around said compression member and having spaced portions of twisted form operatively connected to said strut, and said tie member being of twisted form and extending between said spaced portions of said tension member.
31. A truck side frame comprising a compression member, a strut, and tension means combined in trussed relation, said tension means involving spaced elements each of which is of twisted form.
32. A truck side frame comprising a compression member, a strut, and tension means combined therewith in trussed relation, said tension means involving spaced elements of uniform cross section, each of said spaced elements being of twisted form.
33. A truck side frame comprising a compression member, a strut, and a tension member, said tension member being formed as an endless band looped around opposite ends of said compression member, portions of said band being of twisted form.
34. A truck side frame comprising a compression member, a strut, and a tension member, said tension member being formed as a band of uniform cross section looped around opposite ends of said compression member, portions of said band extending between said compression member and said strut being spaced and of twisted form.
- In testimony whereof I affix my signature.

DONALD S. BARROWS.
